UNITED STATES PATENT OFFICE.

LESLIE E. EATON, OF KANSAS CITY, MISSOURI, ASSIGNOR OF ONE-HALF TO CEDRIC E. GRIFFIN, OF KANSAS CITY, MISSOURI.

SWAGING MACHINE FOR ARTIFICIAL DENTURES.

Application filed February 7, 1925. Serial No. 7,583.

My invention relates to swaging machines, and my object is to provide a simple, compact and relatively inexpensive machine of this character whereby a powerful blow may be delivered for swaging crowns, metal plates and other articles pertaining to artificial denture.

6 In order that the invention may be fully understood, reference will now be had to the accompanying drawings, in which:

Fig. 1 is a vertical sectional view of the machine.

Fig. 2 is a plan view of the machine.

15 Fig. 3 is a transverse section on line III—III of Fig. 1.

In carrying out the invention, I employ a relatively heavy base 2, which may if desired be bolted or otherwise secured to a work bench or other substantial support.

20 4 designates a pair of vertically-disposed guide rods, which are secured at their lower ends to the base 2 and united at their upper ends by a yoke 6 having a central bore 8 through which a vertically-disposed screw 10 freely extends. The yoke 6 has a feather 7, which projects into a groove 9 extending longitudinally of the screw 10 to prevent the same from rotating.

25 12 designates a bevel gear threaded upon the screw 10 and constituting a nut for adjusting said screw up and down. The bevel gear 12 intermeshes with a bevel gear 14 fixedly-mounted upon a shaft 16 journaled in a bearing 18 projecting upwardly from the yoke 6. The shaft 16 is also provided with a fixedly-mounted fly wheel 20, which may be rotated clockwise and anticlockwise, by suitable means, such, for instance, as a handle 22.

30 40 The lower end of the screw 10 is provided with a trip lever 24 connected thereto by a pivot 26 and provided at its lower end with an antifriction roller 28, for a purpose which will hereinafter appear.

45 50 30 designates an adjustable stop threaded in the yoke 6 and depending into the path of the trip lever 24 to cause the same to rock on its pivot 26 and release a vertically-movable ram 32 of suitable weight, and provided at its upper portion with an integral cross head 34, reciprocably mounted on the guide rods 4 and provided at its upper portion with a hook 36 adapted to engage over the anti-friction roller 28.

Coil springs 40 loosely embracing the guide rods 4, are interposed between the yoke 6 and the cross head 34 to force the same and the ram 32 downwardly and cause said ram to deliver a powerful blow upon any article placed upon the base 2, which has a pocket 44 containing a suitable shock absorber 42, such, for instance, as ground cork, to prevent undue shock being imparted to the support upon which the machine rests.

46 designates a container which is removably seated upon the shock absorber 42 and adapted to hold a die or model with the article to be swaged thereon. In Fig. 1, I have shown a metal plate B in position to be swaged upon a model A, which is embedded in suitable means such as shot or putty C, which distributes the force of the blow from the ram 32 uniformly over the plate B. The container 46 is provided with a removable bottom 48 and a metal or other substantial follower plate 50 covered with a leather or other suitable cushion 52.

In practice the ram 32 is raised a suitable distance to give access to the pocket 44 by engaging the roller 28 under the hook 36 and raising the screw 10 by operating the fly wheel 20 and the bevel gears 14 and 12. The model A and the metal plate B are then placed within the container 46 and surrounded with the putty C upon which the follower plate 50 is then placed, the removable bottom 48 having been previously placed in position in the container 46. The screw 10 is then raised as before and carries the upper end of the trip lever 24 against the stop 30, which cooperates with the upwardly moving screw 10 in rocking the trip lever 24 upon its pivot 26 to the dotted position Fig. 1, thereby causing the roller 28 to release the hook 36. The relatively heavy ram 32 then descends by the force of gravity and the action of the coil springs 40 and strikes a heavy blow upon the follower plate 50, the force of the blow causing the putty C to shape the metal plate B to the model A. As the ram 32 impinges against the follower plate 50, or rather its leather cushion 52, shock to the work bench or other support is reduced to a minimum through the intermediacy of the shock absorber 42. After the metal plate B has been properly fitted to the model A, the container 46 is removed from the pocket 44 and inverted, so that pressure may be applied to the bot-

85 90 95 100 105

tom 48 to cause the same to force the putty C, together with the model A and plate B from the container 46, the bore of which tapers towards its upper end so that its contents can be readily removed when it is inverted as stated.

The upper surface 56 of the hook 36 is of sloping formation, so that when the screw 10 is lowered the roller 28 will contact and be guided by said upper surface into the cavity 58 of the hook 36, so that the ram 32 may be again lifted preparatory to delivering another blow.

From the foregoing description it is apparent that I have provided a machine embodying the advantages above pointed out, and while I have shown and described the preferred construction, combination and arrangement of parts, I reserve the right to make such changes as properly fall within the spirit and scope of the invention as claimed.

Having thus described my invention, what I claim and desire to secure by Letters Patent, is:

1. A machine of the character described consisting of a base adapted to support articles, guides extending upwardly from said base, a yoke uniting the upper ends of said guides, a screw free to move vertically but held from rotary movement in said yoke, rotary mechanism for moving said screw up and down, a ram operably mounted on the guides, means connected to the screw for raising said ram and means for disengaging said raising means from the ram so that the same may descend and deliver a blow to an article on the base of the machine.

2. A machine of the character described consisting of suitably supported vertical guides, a member uniting the upper portions of said guides, a screw extending vertically through said member, mechanism including a rotary element threaded upon said screw for moving the same up and down, a ram mounted to move up and down on the guides, and a trip lever mounted on the screw for raising the ram and then releasing the same so that it may descend.

3. A machine of the character described consisting of a base, a guide extending upwardly from said base, a yoke at the upper portion of said guide, a screw extending vertically through said yoke, manually-controlled mechanism including a rotary element threaded upon said screw for moving the screw up and down, a ram operably mounted on the guide, means carried by the screw for raising said ram, and a member adjustably mounted in the yoke and adapted to disen-

gage said raising means from the ram so that the same may descend.

4. A machine of the character described consisting of suitably supported vertical guides, a member uniting the upper portions of said guides, a screw extending vertically through said member, mechanism including a rotary element threaded upon said screw for moving the same up and down, a ram mounted to move up and down on the guides, a trip lever mounted on the screw for raising the ram and releasing the same so that it may descend, and spring means interposed between said ram and the member uniting the upper portions of the guides for accelerating the descent of the ram.

5. A machine of the character described consisting of a base having a pocket, shock absorbing means in said pocket, guides extending upwardly from said base, a yoke uniting the upper ends of said guides, a screw extending vertically through said yoke, mechanism including a rotary element threaded upon said screw for moving the same up and down, a ram operably mounted on the guides, and means carried by the screw for raising said ram and then releasing the same so that it may descend and deliver a blow upon the shock absorber.

6. A machine of the character described consisting of suitably supported guides, a member uniting the upper portions of said guides, a screw extending vertically through said member, a gear wheel threaded upon said screw for raising and lowering the latter and resting upon the member uniting the upper portions of the guides, a second gear wheel for rotating the first gear wheel, a shaft upon which said second gear wheel is fixedly mounted, manually-controlled means for rotating said shaft, a ram mounted to move up and down on the guides, and a trip lever mounted on the screw for raising the ram and then releasing the same so that it may descend.

7. A machine of the character described consisting of a base, guides extending upwardly from said base, a yoke uniting the upper ends of said guides, a screw extending vertically through said yoke, mechanism for moving said screw up and down, a ram having a cross head slidably engaging the guides, a hook in the upper end of said ram, a trip lever carried by the screw for engaging said hook and raising the ram, and a member threaded in the yoke for disengaging said trip lever from the ram so that the same may descend.

In testimony whereof I affix my signature.

LESLIE E. EATON.
